UNITED STATES PATENT OFFICE.

FREDERICK G. YAWMAN, OF ROCHESTER, NEW YORK.

COPY-HOLDER.

1,262,728.

Specification of Letters Patent. Patented Apr. 16, 1918.

Application filed April 17, 1916. Serial No. 91,584.

To all whom it may concern:

Be it known that I, FREDERICK G. YAWMAN, a citizen of the United States, and resident of Rochester, in the county of 5 Monroe and State of New York, have invented certain new and useful Improvements in Copy-Holders, of which the following is a specification.

The present invention relates to copy 10 holders and more particularly to the type in which a work-supporting member and a line guide are caused to move relatively to each other by an operating mechanism which may be disconnected from the mov- 15 able part in order to permit the latter to return to starting position, and an object of this invention is to provide an improved operating mechanism which may be readily manipulated and, at the same time, is in- 20 expensive to manufacture and not liable to get out of order. Another object of the invention is to provide a line guide which can be adjusted to different lines of vision and, at the same time, will accommodate 25 itself to work of different thicknesses. A further object of the invention is to pro- 30 vide a work clamping means which will operate to apply a binding action on the work in proportion to the weight of the work so that heavy work will not release 35 itself from the clamping action.

To these and other ends, the invention consists of certain parts and combinations of parts all of which will be hereinafter 40 described, the novel features being pointed out in the appended claims.

In the drawings:—

Figure 1 is a view in front elevation of 45 a copy holder constructed in accordance with the present invention;

Fig. 2 is a side view of the copy holder;

Fig. 3 is an enlarged view of a portion of the upper part of the copy holder looking from the rear;

Fig. 4 is a section on the line 4—4, Fig. 3;

Fig. 5 is a transverse section of the combined winding drum and counterbalance;

Fig. 6 is a detail view showing the connection between the operating mechanism 50 and the winding drum;

Fig. 7 is a detail view of the line guide showing different positions of the latter in dotted lines;

Fig. 8 is a section on the line 8—8, Fig. 2; and

Fig. 9 is an enlarged section on the line 9—9, Fig. 1.

In the illustrated embodiment of the invention, the relative movement between the line guide and the work holder is effected by mounting the line guide on the stationary frame and moving the work holder on such frame. The stationary frame preferably embodies a base portion 1 formed of sheet metal bent into U-shape in cross section, and having standards or guides 2 rising therefrom in parallel relation. The lower ends of the guides pass through openings in the base 1 and are anchored on cross pieces 3 within said base, the ends of the cross pieces being turned downwardly and secured by rivets 4. The upper ends of the standards or guides 2 are reduced at 5, and these reduced portions are surrounded by sleeves 6 on the ends of a cross plate 7.

The work holder is preferably in the form of a sheet-metal plate 8 having its opposite vertical edges formed into tubes 9, which surround and operate upon the standards or guides 2. On this work holder, the work clamping means is arranged and to this end the upper edge of the support is formed with a bead 10 in spaced relation to the upper ends of the tubes 9. Within this bead 10 the rolled upper edge of a plate 11 is secured, the lower edge of the plate 11 being also rolled and resting upon the upper ends of the tubes 9. The plate 11 extends from opposite sides of the work holder and on the extended portions forwardly and downwardly-projecting arms 12 are arranged. On these arms is supported the clamping device for engaging the upper portion of the work.

This clamping device is preferably in the form of a rod or bar 13 having friction devices such as rubber sleeves 14 thereon, and provided at its ends with laterally-turned portions 15 from which extend bearing portions 16 turning in the arms 12. Beyond 100 the bearing portions 16 the stock is bent into loops which serve as finger pieces for swinging the clamp 13 on the pivot or bearing portions 16, this arrangement making the clamping portion eccentric with reference to the bearing or pivot portions 16. Two coiled

springs 18 are each secured at one end to the clamping portion 13 and at the other end to one of the inwardly-extending lugs or projections 19 on the ends of the arms 12. 5 These springs tend to swing the clamping portion 13 toward the work holder at a point above the turning axis of said clamp, so that the weight of the work tends to draw the clamp more firmly toward the work-holder plate 8. If the clamping portion 13 be swung to the opposite side of the vertical line intersecting the turning axis, then the springs 18 will tend to hold the clamping portion 13 away from the work-supporting 10 plate 8. Stops 20 are bent inwardly from the arms 12 to coöperate with the laterally-turned or offset portions 15 and limit the outward movement of the clamping portion 13. 15 It is desirable, in some instances, as with stenographers' note books, not only to clamp the work in order to support it in the work holder, but also to hold back leaves over the upper portion of the work holder and, to this 20 end, a leaf-holding device is employed comprising preferably a helically-coiled spring 21 secured, at its ends 22, to the upper portions of the arms 12 in close proximity to the upper edge of the work holder. This spring 25 may be readily flexed laterally to permit the introduction of leaves beneath the same and will spring back in place to hold such leaves. When the work is withdrawn from the work clamping portion 13, the leaves 30 will slide from under the leaf-holding device without any manipulation of the latter. The stationary line guide is preferably in the form of a plate 23 having a rolled edge 24 mounted to turn on a supporting part 25. 35 This supporting part preferably has rearwardly-extending arms 26 with inwardly-turned portions 27 at their ends journaled in sleeves 28 which, in turn, are supported on outwardly-extending eccentrically-arranged 40 arms 29 on an oscillatory supporting member 30 mounted to turn in sleeves 31 on the rear face of the cross plate 7. This mounting of the line guide gives to the latter a wide range of adjustment, not only in a vertical direction, but also toward and from the work holder, so that work of different thicknesses may be accommodated between the line guide and the work-supporting plate. 45 The work-supporting plate or member 8 is 50 preferably counterbalanced and, to this end, a tape 32, secured at one end at 33 to the plate 8, is looped about a pulley 34 on the rear face of the cross plate 7, and is secured, at its other end, at 35 to a drum 36 which is 55 mounted on a shaft 37 on the base 1. Within this drum a volute spring 38 is arranged with one end secured at 39 to the drum, and the other end secured at 40 to the shaft 37 on which the drum turns, thus providing a 60 counterbalance for the work-holding plate 8.

The mechanism for raising the work holding plate preferably embodies an operating member in the form of a hand-wheel 41, mounted on a sleeve 42 which is journaled at 43 at the outer end of a forward extension 44 on the base 1 at the right-hand side of the machine. Arranged within said sleeve 42 is a shaft 45 which has a pin-and-slot connection 46 with the sleeve, and has its forward end projecting in front of the operator 41, 70 where it is provided with a finger piece 47 for moving the shaft 45 axially relatively to the sleeve 42. The pin-and-slot connection 46 causes the shaft 45 to turn with the sleeve. The shaft 45 is also journaled at 48 in the lateral extension 44 at the base frame, and carries at its rear end a beveled gear 49 meshing with a beveled gear 50 formed on the counterbalancing drum 36. A coiled spring 51 surrounds the shaft 45 and abuts 80 the bearing 48 at one end, and the collar 52 on the shaft at the other end. A rolled portion 53 on the forward extension 44 incloses the coiled spring 51. The spring acts in a direction to maintain the gear 49 in mesh with the gear 50 so that when the operator 41 is turned in one direction it will turn the counterbalancing drum 36, winding the tape 32 on the drum and thereby elevating the work holder. 95

To prevent the rotation of the gear 49 in the opposite direction, a pawl 54 is mounted to turn on a stub shaft 55 and to move axially of the shaft. With this pawl two lugs 56 are carried, said lugs engaging opposite faces of the gear 49 so that when the gear 49 is moved axially the axial movement will be transmitted to the pawl 54 by the projections 56. A spring 57 maintains the pawl 54 in engagement with the gear 49. 100

The operation of the invention is as follows: The work is secured beneath the work clamping member 13 and between the line guide 23 and the work support 8, the line guide being adjusted to the line of sight. 110 The operator, to shift the work, turns the operating member 41 a distance corresponding to the spacing desired. This is repeated until the work holder is required to be returned to its initial position, the return being effected by pressing inwardly on the finger piece 47, thereby causing the gear 49 to disengage with the gear 50, when the work holder or work will drop by gravity. The counterbalancing arm absorbs all 115 of the shock of this descent due to the increase of tension in the spring 38 as the work holder approaches its lowermost position. Should it be desired to stop the work holder before it reaches its lowermost position, the thumb-piece 47 is released at the desired point, and the gear 49 quickly moves into mesh with the gear 50, thus preventing any 120 further movement of the work holder. 125

A copy holder constructed in accordance 130

with this invention is inexpensive to manufacture, simple in its operation, and durable in its use. The supporting frame is of novel construction and may be made from sheet metal and steel rods. The work holder is counterbalanced and in this way no shock absorbers are required. The mechanism for raising the work holder is readily operated and is not liable to get out of order. 5 The operator may obtain any desired line spacing by properly manipulating the operating member which is rotated continuously in one direction. The center of the work holder is easily secured from a point 10 adjacent the operating member. The line guide is adjustable to any line of sight and is readily accommodated to work of different thicknesses. The work clamping device operates in a direction to apply a binding 15 action on the work in proportion to the weight of the work.

It will be noted that the two coöperating gears form a make-and-break motion-transmitting connection between the rotary shaft 20 and the movable element of the copy holder and that this connection is controlled by a movement of the shaft separate from its 25 rotary movement.

What I claim as my invention and desire 30 to secure by Letters Patent is:—

1. A copy holder comprising a work holder, a supporting frame including a base portion formed from sheet-metal of inverted U-shape in horizontal cross-section, 35 cross pieces within said base portion, uprights on which the work holder is guided secured to said cross pieces and extending through the top of the base, and connecting means between said uprights and a line 40 marker supported on the supporting frame.

2. A copy holder comprising a work holder, a supporting frame including a base portion, uprights on which the work holder is guided extending upwardly from 45 said base portion and having reduced upper ends, and a cross plate having tubular portions at its ends fitting about said reduced portions and a line marker supported on the supporting frame.

3. A copy holder comprising a supporting frame, a work holder movable vertically on the frame, a drum arranged on the supporting frame, a flexible connection between said drum and the work holder, means connected 55 to the drum for turning the latter, and a spring acting on said drum to counterbalance the work holder.

4. A copy holder comprising a supporting frame, a work holder movable vertically on 60 the frame, a spring drum supported on one of said parts and having a flexible connection with the other part adapted to be wound on the drum to counterbalance the work holder, and means for raising the work 65 holder, said means being adapted to be

thrown out of connection with the work holder to permit the latter to lower under its own weight.

5. A copy holder comprising a supporting frame, a work holder movable vertically on the frame, a drum arranged on the supporting frame near the base thereof with its axis extending transversely of the plane of movement of the work holder, a flexible connection between the drum and the work 70 holder, a gear on the drum, and a gear arranged with its axis parallel to the axis of the drum and movable axially into and out of mesh with the drum and a shaft extending in front of the work holder from the 75 axially movable gear by which the latter is turned.

6. A copy holder comprising a supporting frame, a work holder movable vertically on said frame, a gear arranged on the supporting frame and having connection with the work holder to raise the latter, a gear arranged with its axis parallel to the axis of the first named gear and movable axially 80 into and out of mesh with the first named gear, an axially movable shaft secured to the axially movable gear, a sleeve surrounding said shaft and connected to the latter to cause the same to turn with the sleeve, and a 85 hand piece on said sleeve.

7. A copy holder comprising a supporting frame, a work holder vertically movable on the frame, an operating mechanism for moving the work holder on the frame embodying a rotary operating member, an axially 100 movable shaft connected to the operating member and having a finger piece portion arranged in proximity thereto, a gear carried by said shaft, and connections between said gear and the movable work holder. 105

8. A copy holder comprising a supporting frame, a work holder vertically movable on the frame, an operating mechanism for moving the work holder on the frame embodying a rotary operating member, an axially 110 movable shaft connected to the rotary operating member and having a finger piece portion arranged in proximity thereto, a gear carried by said shaft, a pawl mounted to move with said gear, and connections between the gear and the movable work holder. 115

9. A copy holder comprising a supporting frame, a work holder vertically movable on the frame, a line guide and two supporting members for the line guide pivotally 120 connected together, one of said supporting members carrying the line guide and the other of said supporting members being pivotally connected to the supporting frame.

10. A copy holder comprising a supporting frame, a work holder movable vertically on the frame, a line guide, and two supporting members for the line guide, one of the supporting members being pivotally connected to a supporting frame at the rear 125 130

of the work holder and the other of said supporting members being pivotally connected to the first-named supporting members and arranged in front of the work holder, the last named supporting member carrying the line guide.

11. A copy holder comprising a supporting frame, a work holder movable vertically on the frame, a line guide and two supporting members for the line guide, one of said supporting members being pivoted to the supporting frame in the rear of the work holder and having arms arranged eccentrically with relation to the turning axis of the supporting member, and the other of said supporting members having a portion lying in front of the work holder and also arms extending rearwardly from said portion and pivotally connected to the eccentrically arranged arms on the other supporting member, the line guide being pivoted on said last named supporting member.

12. A copy holder comprising a supporting frame, a work holder movable vertically on the frame, a line guide, and two supporting members for the line guide, one of the supporting members being pivotally connected to the supporting frame and the other supporting member being pivotally connected with the first named supporting member, one of said supporting members being offset rearwardly of its pivotal center and the other being offset forwardly of its pivotal center.

13. In a copy holder having a work support and a line guide; means for effecting relative movement between the work support and the line guide comprising two cooperating rotary gears, means for holding one of said gears from turning in one direction, means connecting the other gear to the moving part, and means for supporting said first-named gear so that it may move out of connection with the other gear to permit the moving part to return to its initial position.

14. In a copy holder having a work support and a line guide; means for effecting a relative movement between the work support and the line guide comprising two cooperating rotary gears, one connected to the moving part, a pawl for holding the other gear from turning in one direction, a shaft on which the last-named gear is mounted,

and means for supporting said shaft for two movements, one to turn the said gear in one direction and the other to disconnect said gear from the first-named gear so that the moving part may return to its initial position.

15. In a copy holder having a work support and a line guide; means for effecting a relative movement between the work support and the line guide comprising a rotary shaft provided with an operator, connection between the shaft and the moving part, and means for supporting the rotary shaft for its rotary movement and also for a second movement separate from its feeding movement to break the connection between said shaft and the moving part.

16. In a copy holder having a work support and a line guide; means for effecting a relative movement between the work support and the line guide comprising a rotary shaft having a movement separate from its rotary movement, a ratchet for preventing the rotation of the shaft in one direction, and a make-and-break, motion-transmitting connection between the rotary shaft and the moving part, controlled by the separate movement of the shaft.

17. In a copy holder having a work support and a line guide; means for effecting relative movement between the work support and the line guide comprising a rotary operator, a pawl for preventing the turning of said operator in a reverse direction, and a make-and-break, motion-transmitting connection between the operator and the moving part of the copy holder, controlled by the rotary operator.

18. A copy holder as set forth in claim 13 combined with a counterbalancing device for the moving part, acting to retard the return of said moving part when the gears are disconnected.

19. A copy holder as set forth in claim 13 combined with a volute counterbalancing coil connected to the gear that is connected to the moving part so as to retard the return movement when the gears are disconnected.

20. A copy holder as set forth in claim 13 combined with a spring normally tending to hold the gears in coöperation.

FRED G. YAWMAN.
